UNITED STATES PATENT OFFICE.

THOMAS A. COSGRIFF, OF FULDA, MINNESOTA.

ENVELOP STAMP AND SEALER.

1,233,033.

Specification of Letters Patent. Patented July 10, 1917.

Application filed July 7, 1916. Serial No. 107,925.

To all whom it may concern:

Be it known that I, THOMAS A. COSGRIFF, a citizen of the United States, and a resident of Fulda, in the county of Murray 5 and State of Minnesota, have invented certain new and useful Improvements in Envelope Stamps and Sealers, of which the following is a specification.

The present invention relates to means for 10 sealing and printing the return cards thereon.

The invention has for its primary object the production of an improved device embodying for moistening the gummed edge 15 of an envelop, means for compressing the envelop to seal it and means for printing the return card on the envelop while the latter is compressed.

A further object of the invention is the 20 production of an improved envelop sealing and printing device inexpensive in manufacture and thoroughly efficient in operation.

With these and other objects in view, the 25 invention consisting in the construction, combination and novel arrangement of parts, will be fully understood from the following description, reference being had to the accompanying drawings, which form a 30 part of this application and in which like characters of reference indicate corresponding parts throughout the several views, of which,—

Figure 1 is a plan of a device constructed 35 in accordance with the invention; Fig. 2 is a transverse section taken on the line 2—2 of Fig. 1 with the printing device in operative position on the envelop; Fig. 3 is an 40 inverted plan of the printing stamp; and Fig. 5 is a reduced similar view of the presser plate.

Although I have illustrated and herein-after described the preferred embodiment 45 of the invention, I would not be understood as being limited to the specific structure chosen for illustration for various alterations and modifications in the details of construction, and arrangement of parts may 50 be made without departing from the spirit and scope of the invention as defined in the appended claims.

Referring, now, to the illustrations, 6, represents a base plate of any suitable material and preferably somewhat longer and 55 wider than the envelops with which the de-

vice is to be employed. Above the base plate is mounted a presser plate, 7. The rear edge of the presser-plate is substantially flush with and hinged to the corresponding edge 60 of the base plate, as by providing studs, 8, on the side edges of the presser plate adjacent the rear edge thereof. The studs are pivoted in suitable bearings, 9, on the base plate. The presser-plate is preferably narrower than the lower plate in order not to 65 conceal the addresses on the envelops.

At the sides of the presser-plate are forwardly extending arms, 10, which rest upon torsion springs, 11, secured to the base plate 70 as at, 12. The said springs serve to normally maintain the presser-plate yieldably in spaced relation to the companion plate to permit the convenient introduction and 75 removal of the envelops.

Extending longitudinally of and above the presser-plate is a shaft, 13, the ends of which are freely supported in bearings, 14, on the sides of the base plate. The shaft is formed with an elongated cam, 15, and on 80 the end of the shaft is provided a lever which is operated to rock the shaft and bring the cam into engagement with the presser-plate to firmly press the latter upon the envelop. The upper left corner of the 85 presser-plate is cut away as at, 31, in order to expose the portions of the envelops upon which the return cards are to be stamped. At the rear of the base plate are secured up- 90 right bearings, 17, in which are mounted 95 the ends of a rock-shaft, 18, the intermediate portion of which is flat sided or square in transverse section. Upon the rock shaft is slidably mounted a sleeve, 20, carrying a forwardly-extending lever arm, 21, from 95 which depends a block, 22, provided on its under side with type characters, 23. The printing block, 22, is normally held in an upwardly-inclined position, as shown in Fig. 3, by means of a spring, 24, which encircles the shaft, 18, and has one end secured to the shaft and the other to the adjacent bearing, 17. Upon the presser-plate, 7, is mounted a suitable type-inking element, or stamp pad, 25. At the rear edge 105 of the base plate is mounted an upright, 26, supporting a box, 27, or other suitable container, in which is a sponge, 28, or other suitable moistening means.

In operation the gummed edge of the 110 envelop is drawn across the moistener, 28. The envelop (which is represented as 29)

is then inserted face upward, between the base and presser-plates. The lever, 16, is then moved forwardly, whereupon, the cam, 15, will press the plate, 7, into firm engagement with the envelop and thus cause the gummed flap to firmly adhere to the back of the envelop.

While the envelop is thus firmly held in position the stamping lever, 21, is depressed 10 above the pad, 25, to bring the type in contact with the pad, as shown by dotted lines in Fig. 3. The stamp is then moved along the shaft, 18, to a position above the presser-plate opening, 31, and the lever again depressed to print the return card upon the envelop. The lever, 16, is then moved rearwardly, whereupon, the springs 11, raise 15 the presser plate and permit the convenient removal of the sealed and printed envelop.

Upon either the upper side of the base plate or the underside of the presser-plate may be mounted raised strips, 30, which are so positioned as to impinge the envelop on 25 lines coincident with the gummed edge of the envelop flap.

Obviously the device may be so constructed as to accommodate envelops of all sizes.

Having thus described my invention, what I claim as new and desire to secure by Letters Patent, is,—

1. In a device for printing and sealing envelops, a base plate upon which envelops 35 may be placed, a presser plate hinged at one edge to the base plate, and narrower than the envelops, extended parts on the free edge of the presser plate, yieldable means between said parts and the base plate, the hinged 40 edge of the presser plate having an opening to expose portions of the envelops to be printed and a printing stamp operable to

impress the said portions within the opening, and means for depressing the presser plate to impinge the envelops. 45

2. In a device for printing and sealing envelops, a base plate upon which envelops may be placed, a presser plate hinged at one edge to the base plate and narrower than the envelops, extended parts on the 50 free edge of the presser plate, yieldable means between said parts and the base plate, the hinged edge of the presser plate having an opening to expose portions of the envelops to be printed, a cam-shaft supported 55 above the presser plate by the base plate and operable to depress the presser plate to impinge the envelops, and a printing device operable to impress the portions of the envelops within the opening while the presser 60 plate is depressed.

3. In a device for printing and sealing envelops, a base plate upon which envelops may be placed, a presser plate hinged at one edge to the base plate and narrower than the 65 envelops, extended parts on the free edge of the presser plate, yieldable means between said parts and the base plate, the hinged edge of the presser plate having an opening to expose portions of the envelops to be 70 printed, a cam shaft supported above the presser plate by the base plate and operable to depress the presser plate to impinge the envelops, strips on one of said plates positioned to impinge the envelops on lines coincident with the gummed edges of their flaps, and a printing device operable to impress the portions of the envelops within the opening while the presser plate is depressed. 75

In testimony, whereof, I have hereunto set my hand.

THOMAS A. COSGRIFF.
